UNITED STATES PATENT OFFICE.

HOWARD WILLIAMS, OF TORONTO, ONTARIO, CANADA.

TIE-SUPPORT.

1,124,370.

Specification of Letters Patent. Patented Jan. 12, 1915.

Application filed August 17, 1914. Serial No. 857,224.

To all whom it may concern:

Be it known that I, HOWARD WILLIAMS, of the city of Toronto, in the county of York, in the Province of Ontario, Canada, have invented certain new and useful Improvements in Tie-Supports, of which the following is the specification.

My invention relates to improvements in tie supports adapted to secure a tie in folded position beneath the turned-down portion of a stand-up turned-down collar and the object of the invention is to devise a simple means which will serve as a support and a form for the knot of the tie and which 10 may be readily connected to the collar stud to be supported thereby beneath the flaps of the collar and it consists essentially of a plate having the upper portion curved both in a vertical and a horizontal plane 15 and a stem depending centrally therefrom having an enlarged upper end having curved edges and gradually curved back toward such edges and a horizontal open ended slot having an enlarged inner end 20 formed in the outer end of the stem as hereinafter more particularly explained by the following specification.

Figure 1, is a perspective view of my device. Figs. 2, 3, 4 and 5 are perspective 30 views showing the method of folding the tie around the support. Fig. 6, is a perspective view showing a tie and my tie support connected to a collar. Fig. 7, is a perspective view showing my tie support 35 in position connected to a collar with the tie removed.

In the drawings like letters of reference indicate corresponding parts in each figure.

A is a T-plate comprising an upper portion A' curved both in a horizontal and a vertical plane so as to form tongues which are preferably spring tongues A² and A³.

A⁴ is a stem which depends centrally from the portion A' such stem comprising an upper enlarged portion A⁵ having curved edges A⁶ such portion A⁵ being curved in a horizontal plane rearwardly in proximity to such edges so as to form a rounded edge A⁷. The lower end A⁸ of the stem is formed 45 flat with a slot A⁹ extending inwardly from one edge thereof such slot being enlarged preferably into circular form at its inner end, such enlarged portion being located centrally of the stem.

2 is a tie of any suitable form. When 55 placing the tie in position upon the form it is first passed over the top edge thereof as shown in Fig. 2 and then around the top enlarged portion of the stem to the back of the form and then upwardly as 60 shown in Fig. 3. The upwardly extending end as shown in Fig. 3 is then passed downwardly through the loop portion 3 of the tie so as to form the other depending tie end as shown in Fig. 4. In Fig. 5, I show 65 the reverse side of the tie form as shown in Fig. 4 the slotted end of the depending stem extending free of the fold of the tie. When placing the tie in position in the collar all it is necessary to do is to slip the 70 upper portion A' beneath the turned-down flaps of the collar and upwardly against the interior fold of the collar. When in this position the slot A⁹ is then passed behind the head of the stud securing the collar at 75 the front. Also, in this position the tendency of the collar is to force the form downwardly and therefore, the stem of the stud into the upper portion of the enlarged portion of the slot thereby preventing easy 80 withdrawal. The ends of the tongues A² and A³ having a slight spring tension against the collar serve to further hold the slot therein from disengaging the stud.

From this description it will be seen that 85 I have devised a very simple form of tie support which will hold the knot of the tie neatly and in proper shape and which will form a firm securing means for holding the tie in position beneath a turned-down collar. 90

What I claim as my invention is.

A tie form and support comprising a T-shaped plate the horizontal arms of which are curved both in the vertical and a horizontal plane and the vertical arm of which 95 is provided with an enlargement at its upper end having curved edges such enlargement being curved rearwardly toward such curved edges and having a horizontal open ended slot extending into the lower end of 100 the vertical arm having an end enlargement located centrally of the stem, as and for the purpose specified.

HOWARD WILLIAMS.
